UNITED STATES PATENT OFFICE.

GEORG SCHROETER, OF BERLIN, GERMANY.

HYDROGENATION OF NAPHTHALENE.

No Drawing.

Application filed August 29, 1921. Serial No. 496,639.

(GRANTED UNDER THE PROVISIONS OF THE ACT OF MARCH 3, 1921, 41 STAT. L., 1313.)

To all whom it may concern:

Be it known that I, GEORG SCHROETER, a citizen of the German Republic, residing at Berlin, Germany, have invented certain new and useful Improvements in Hydrogenation of Naphthalene (for which I have filed applications in Germany February 24, 1915, Patent No. 324,861, issued to assignee, Tetralin G. m. b. H.; in Germany December 7, 1915, Patent No. 324,862, issued to assignee, Tetralin G. m. b. H.; in Germany May 13, 1916, Patent No. 324,863, issued to assignee, Tetralin G. m. b. H.; and in Belgium filed May 31, 1920; in France filed May 21, 1920; in England filed July 8, 1920; in Italy filed June 30, 1920; in Austria filed April 15, 1920; in Hungary filed July 31, 1917; in Netherlands filed April 21, 1920; in Switzerland filed June 30, 1920, and in Czechoslovakia filed July 10, 1920), of which the following is a specification.

The present invention relates to the hydrogenation of commercial naphthalene in a technical manner, whereby products can be produced on a technical scale which are suitable for various purposes, such as substitutes for mineral oil distillates, including gasoline, burning oils and lubricating oils.

The process involves, first, the removal from commercial naphthalene of substances which, in accordance with the present invention, have been found to exert a poisoning action on hydrogenation catalysts, and the subsequent hydrogenation of the naphthalene while in the presence of a metal catalyst.

The hydrogenation of naphthalene, broadly stated, has heretofore been proposed, but seems not to have come into commercial use prior to the present invention.

Among the methods heretofore proposed may be mentioned the treatment of naphthalene at a high temperature with hydriodic acid (Berichte, vol. 16, page 3028), or by heating with sodium and amyl alcohol (Berichte, vol. 23, page 1561). These processes were so expensive that they could not be commercially employed.

Processes have also been proposed for the hydrogenation of naphthalene by treating the naphthalene with hydrogen gas in the presence of a catalyst such as nickel. These processes, to the best of my knowledge, have

not been commercially used, prior to my present invention. 55

The present invention, on the other hand, is easily and economically carried out and can be used on a large scale and has the advantage that the catalyst employed can be used for a long time, or used for the hydrogenation of large quantities of naphthalene. 60

The process is divided into two stages or steps, first the purification, and second the hydrogenation.

It has long been known that even the purest commercial (i. e. technically produced) naphthalene stubbornly retains certain small amounts of impurities, especially methylated coumarone and corresponding sulfur compounds, which substances cause a red coloration when commercial naphthalene is subjected to treatment with hot concentrated sulfuric acid. It was also known that by boiling commercial naphthalene with acetate of mercury in alcoholic solution, certain 75 mercury compounds were produced which were not mercury compounds of thionaphthalenes. It has also previously been known that ordinary purified naphthalene contains sulfur compounds and it has been proposed to purify naphthalene from these sulfur compounds by repeated crystallization from various organic solvents. Such processes would, however, not be commercially feasible in connection with the commercial hydrogenation of naphthalene. 80

In accordance with the present invention, the naphthalene treated, namely, commercial or technical naphthalene, can be purified by treating it in a molten state with fuller's earth, infusorial earth, animal charcoal or the like, that is, any porous and finely-divided material, which naturally contains small quantities of metal oxides, such as lime, and which material is also capable of absorbing or adsorbing coloring matters, resinous substances or other materials of high molecular weight. The naphthalene can then be removed by filtering or by distillation at a temperature which is not sufficiently high to cause undesired side reactions, for example in vacuo. This purification may sometimes not be sufficiently complete and a more complete purification can be effected by the use, instead of the above 100 mentioned porous materials alone, of fuller's 105

earth upon which is precipitated a small amount say, 1 or 2% or so, of reduced nickel, reduced iron or other like metal. During this purification step, it is advisable to agitate by stirring, pumping etc., in the presence of hydrogen. The temperature in this operation should be kept above 100° C. These metals also can be used alone in a finely-divided state for the purification of 10 naphthalene. Another method of purifying the naphthalene, which reduces the impurities to a very small quantity, involves the treatment of the molten naphthalene with small percentages of metallic sodium or potassium or other easily melted metals of like properties. In this operation it is advisable to treat the molten naphthalene with, say, from one-half to one and one-half per cent of metallic sodium or potassium at a temperature above 100° C., for several hours.

Another useful method of purifying the naphthalene is by treating the same in a molten state (after a preliminary distillation if desired) with small amounts of metal compounds which contain a metal loosely combined with a non-acid radical or element. Examples of such compounds are the metal-ammonia compounds, metal amids (such as sodium or potassium amid), metal carbides (such as aluminum or calcium carbides), or other metal compounds of acetylene.

It is, of course, to be understood that these various methods of purification above given 35 can be used each by itself, or two or more of these methods can be used in conjunction with each other.

Naphthalene purified according to the above processes does not produce any red 40 coloration when treating with concentrated sulfuric acid and the purification should be so complete that even when the naphthalene so purified is ground up with hot concentrated sulfuric acid and allowed to stand 45 hot for several hours, no substantial amount of red coloration is produced. If it is found that the purification of a particular batch has not been sufficiently completed, it is advisable to again subject this material to a 50 retreatment according to one or the other of the above mentioned processes.

The naphthalene, after its purification, can be separated from the residue of the purifying agents, or from the compounds produced by the union of the impurities with the purifying agents, by hot pressure filtration in hydrogen, or by distillation at a relatively low temperature, distillation in 55 vacuo being a preferred mode of operation.

60 The purified naphthalene can then be subjected to hydrogenation, for example by adding a catalyst such as finely-divided nickel or nickel deposited upon fuller's earth or like carrier in an autoclave under a pressure of, say, 10 atmospheres at a tempera-

ture of over 100° C., and preferably between 150 and 200° C., while agitating.

The following examples of procedure falling within the scope of the present invention are given for the purpose of more fully explaining the matter of the invention, but the scope of the invention is not limited to these specific examples.

Example 1.—100 kilos of commercial naphthalene in a kettle at a temperature 75 above 100° C., are stirred with 5 to 10% or more of finely divided absorbent earth, until a sample of the material, after being substantially separated, shows no red coloration when treated with concentrated sulfuric acid, after standing for some time. The purified naphthalene in molten state is then mixed with 5 to 10% of a catalyst such as fuller's earth carrying 5% or so of reduced nickel placed in an autoclave and subjected to hydrogen under a pressure of, say, 10 atmospheres. The reaction mass is agitated in order to facilitate mixing with hydrogen. The temperature should be kept continuously above 100° C., preferably between 150 80 and 200° C. After 3 kilos of hydrogen have been absorbed (which should require about an hour's time) the liquid material is drawn off, leaving the catalyst in the autoclave 85 and a new batch of 100 kilos of naphthalene is introduced and the operation repeated. This produces substantially pure tetrahydronaphthalene. The product is a colorless liquid which boils at 206 to 207° C., at atmospheric pressure or at about 88° under a pressure of 13 m. m., of mercury, it solidifies 90 at about minus 30° C. Its flash point is 95 75.8° C.

In this example it is not necessary to stop the hydrogenation at the time when the naphthalene has been converted into tetrahydronaphthalene, but the operation can be continued further, in which case the hydrogenation proceeds somewhat more slowly, until 100 after an absorption of 7.5 kgs., of hydrogen (which may require about three hours) the end product will be decahydronaphthalene, $C_{10}H_{18}$, having a boiling point at ordinary atmospheric pressure of 188° C., a boiling point under a pressure of 13 m. m., of mercury of 73 to 74° C., and a flash point of 115 58.5° C.

In this example, if the amount of catalyst is increased, the speed of hydrogenation is accelerated. One may measure the hydrogen consumption or absorption by means of the pressure gauge on the autoclave.

In the production of the tetrahydronaphthalene it has been found in operation of 125 the present process that substantially the entire amount of naphthalene was converted into tetrahydronaphthalene before any material amount of the naphthalene will be converted into more highly hydrogenated 130

products. This fact is somewhat surprising in view of the contrary statements of Willstatter et al. (Berichte vol. 45, page 1474 and vol. 46, page 534).

5 *Example 2.*—100 kilos of commercial naphthalene, e. g., that obtained by hot pressing naphthalene press cake, are stirred in an autoclave with 1% of nickel or iron which has been precipitated on an extending material, such as argillaceous earth, and subjected to hydrogen under pressure for three hours at 150 to 180° C., whereupon the naphthalene is distilled off under reduced pressure from the purifying agents, 10 after it has been shown by a sulfuric acid test (see above) that the purification is complete. The hydrogenation may be carried out in accordance with that given in example 1.

20 *Example 3.*—100 kilos of commercial naphthalene are placed in a kettle or boiler with a distilling tube and receiver to be connected therewith and mixed with 750 grams (three quarters of one percent) of 25 sodium and stirred for 2 or 3 hours at 180 to 200° C., whereupon the naphthalene is distilled off in *vacuo*. This gives a very complete purification of the naphthalene from catalyst poisons. In this example, 30 the sodium can be used with the finely divided porous materials if desired. The testing and hydrogenation may be carried out as above described.

35 *Example 4.*—500 parts of commercial naphthalene, after purification by melting with fuller's earth or other porous materials and filtering from the precipitate, are mixed with 200 parts of a catalytic mixture containing about 25% of finely-divided nickel 40 precipitated on a porous carrier, and heated in a pressure-receptacle with hydrogen to 120 to 150° C., and thereafter hydrogen is pumped in in such quantity that under the temperature and pressure conditions stated sufficient hydrogen is present for the 45 complete hydrogenation of the naphthalene (that is to say to each molecule of naphthalene there are present five molecules of hydrogen). The higher pressures (that is to say pressures substantially above 10 atmospheres) are of little importance, although at pressures between 50 and 100 atmospheres the hydrogenation proceeds a little faster than at pressures of from 3 to 10 atmospheres. Stirring or shaking of the apparatus is not necessary since the catalytic material of the mass retains its spongy structure, nevertheless a very large surface is essential. The course of the reaction can be observed on the manometer provided on the apparatus, which shows a rapid fall, and the operation should be completed in about one and one-half to three hours, at which time the manometer will remain stationary. 55 The damp mass is taken from the apparatus after cooling and the hydrocarbon is pressed off from the catalyst or one pushes the mass out of the apparatus by the hydrogen pressure still remaining therein. The hydrocarbon pressed out is a colorless 60 or slightly yellow and fluorescent liquid and boils at 73 to 74° C., under a pressure of 13 m. m., of mercury or at 188° C., under atmospheric pressure. Upon redistillation the product is entirely colorless, possesses a slight but not disagreeable odor, is indifferent to permanganate and bromine and seems to be identical with the known decahydronaphthalene $C_{10}H_{18}$. It can be used as a substitute for kerosene for lamps, as 65 a motor fuel, as a fine lubricating oil, as a material for the production of explosives and as a starting material for various chemical processes.

If the hydrogenation is not carried out completely the product may consist of decahydronaphthalene mixed with varying quantities of products less highly hydrogenated, whose presence is observed by higher boiling point and higher density of 70 the fraction produced near the end of the distillation operation. One can, therefore, obtain lower hydrogenated products by this process. The catalyst may be reused for the hydrogenation of further quantities of 75 naphthalene, but after many operations the catalyst becomes inefficient and should be regenerated in any suitable manner.

80 *Example 5.*—100 kilos of crude naphthalene in the shape of solid press cake obtained by the warm pressing process from coal tar still residues (after ordinary distillation if the mechanical impurities and higher boiling point tarry components are present in relatively large amount) are treated in a molten state with one kilo of sodium amid by stirring actively in a kettle for three hours, while the naphthalene is in a molten condition. The so treated naphthalene is separated from the other 85 reaction products, preferably by distillation in *vacuo*. This naphthalene is found to give no red color, even after standing for several hours with concentrated sulfuric acid, and can then be hydrogenated according to 90 the process mentioned under example 1, or any other suitable hydrogenation process.

95 In this example it is preferable to employ a temperature of over 100° C. Other purifying agents such as the metal ammonia compounds, potassium amid, metal carbides such as those of aluminum or calcium or metal acetylides, can be employed. The subject matter of this last example is not specifically claimed in the present case, but in a copending case filed concurrently herewith, Serial No. 496,640.

100 It may be remarked that the purification of the naphthalene from those substances which produce red coloration upon treat-

ment with sulfuric acid, not only makes the catalyst last better (i. e., retain its usefulness for a long period), but also it renders the hydrogenation much easier and more readily controllable.

The highly impure varieties of naphthalene which give a deep red color with sulfuric acid, can be purified according to the processes herein described, and subsequently hydrogenated.

The hydrogenation can conveniently be effected at temperatures between 125 and 200° C., and it usually is not advisable to employ temperatures substantially in excess of 200° C.

What is claimed is:

1. In the hydrogenation of naphthalene, the herein described improvement which comprises removing from naphthalene in molten condition all of the bodies which are capable of causing red coloration upon treatment with strong sulfuric acid, and then hydrogenating the product while still in molten condition, by treating with hydrogen in the presence of a hydrogenation catalyst, until it has absorbed such an amount of hydrogen as to form a definite hydrid of naphthalene.

2. A process which comprises treating molten naphthalene, in the absence of material amounts of catalyst poisons, with hydrogen, in the presence of a nickel catalyst, at a temperature above 100° C., while under a pressure of about 10 atmospheres.

3. A process which comprises mixing a finely divided metal catalyst with commercial naphthalene which is free from those impurities which are capable of causing red coloration when treated with strong sulfuric acid, and treating it as a non-flowing mass, with hydrogen under pressure, until it takes up such an amount of hydrogen as corresponds to the formation of a definite hydrid of naphthalene.

4. A process of hydrogenating naphthalene which comprises treating a naphthalene

of commercial grade, but free from all those impurities which are capable of producing a red coloration on treatment of said naphthalene with strong sulfuric acid, with hydrogen in the presence of a hydrogenation catalyst.

5. A process of hydrogenating naphthalene which comprises treating a naphthalene of commercial grade, but free from all those impurities which are capable of producing a red coloration on treatment of said naphthalene with strong sulfuric acid; with hydrogen in the presence of a hydrogenation catalyst under a pressure of about 10 atmospheres and at about 100 to 200° C.

6. In the process of hydrogenating naphthalene, the step which comprises treating a naphthalene of commercial grade, free from all those impurities which are capable of producing a red coloration on treatment of said naphthalene with strong sulfuric acid, with hydrogen in the presence of a hydrogenation catalyst, until the said naphthalene has combined with such a quantity of hydrogen as to produce a definite hydrid of naphthalene.

7. A process of hydrogenating naphthalene which comprises the steps of removing from naphthalene, while in fluid condition, constituents capable of acting as catalyst poisons and then subjecting the purified naphthalene, while still in fluid condition, to the action of hydrogen in the presence of a hydrogenation catalyst.

8. A process of hydrogenating naphthalene which comprises the steps of removing from naphthalene, while at an elevated temperature, constituents capable of acting as catalyst poisons and then subjecting the purified naphthalene, while still at an elevated temperature, to the action of hydrogen in the presence of a hydrogenation catalyst.

In testimony whereof I have signed my name to this specification.

GEORG SCHROETER.
